ARTICLE SORTING CONTROL
ARRANGEMENT

Karl Steinbuch, Reichenbach, near Karlsruhe, and Ulrich Schottle, Stuttgart, Germany, assignors to International Standard Electric Corporation, New York, N.Y., a corporation of Delaware

Filed Mar. 6, 1959, Ser. No. 797,703

Claims priority, application Germany Mar. 8, 1958
3 Claims. (Cl. 209—72)

This invention relates to an articles sorting arrangement in particular for the distribution of mail items, into which the destination of each mail item is fed into a store, by operators who actuate keyboards, and the destination information being in the form of a succession of letters of the name, or in the form of a code, and which then accordingly establishes a predetermined conveying path for said items. The identification of the destination name may be used for directly setting a conveying path or for attaching a marking to the mail items according to the identification. At the respective time positions these markings will then be scanned at arbitrarily located distribution points, and are used for the setting of conveying paths or sections.

In order to solve this problem it has already been proposed to provide a contact arrangement in which the buttons corresponding to the individual letters of the destination names successively establish a sequence of contacts, thus electrically indicating the conveying path. By the evaluating circuit there are evaluated as many of the letters of the completely keyed-in destination names as are necessary for enabling an unambiguous identification of the location.

However, it has proved that this solution is unfavorable, because the number of letters varies within the individual destination names. On the other hand, and in the case of long destination names or such ones which, for being better distinguished, still require an addition such as "on Rhine," there has to be keyed-in a relatively high number of letters.

For overcoming the last-named disadvantage, it has been previously suggested to apply to an evaluation circuit direction criteria representative of the destination of the mail items and to automatically transmit revertive signals from the evaluation circuit to the operator's positions after application to the evaluation circuit of the requisite number of letters denoting a destination.

This arrangement, however, is disadvantageous in that the evaluation circuit must be connected to a particular operator's position for a relatively long time (until the destination storage is complete), and this consequently busies the evaluation circuit.

In accordance with a fundamentally different solution it is possible to key in incomplete destination names of the address and to constitute a code from a number of code letters which are taken from the destination name in accordance with certain rules. As a rule there may be set up a code which will include only the first, third, fourth and last letters of the destination name.

However, as with all coding systems (unless a very long code is used) there will result a remainder of the destination names which are not unambiguously defined by a letter code. This remainder will increase the simpler code system and will decrease with the employment of a more complicated system.

An object of the present invention is to provide an article sorter in which there is used one of the last-mentioned destination name-coding methods. The invention is based on the recognition of the use of the most simple code system for enabling a quick recognition of the code letters within the destination name also to render the

2

arrangement readily operable by less experienced personnel, and to use as few as possible code letters, for achieving short keying times. A limit with respect to the simplification is given by the reasonable number of destination names which cannot be unambiguously represented by the code.

According to the invention there is provided a translator which is arranged in such a way that it will characterize the conveying path to be selected by a code having a number of code letters which is limited, and that it, subsequently to the keying-in by an operator of the code letters which are determinable in advance and in accordance with the most elementary code of the destination names and which are not unambiguously determinable, will transmit a backward signal to the operator's position. This signal will then cause the operator or the sorter to subject the mail item to a special treatment.

It is appropriate to arrange in the conveying path and in advance of a letter-facing or stamp-cancellation device 20 a switching device which, upon the occurrence of the above mentioned signal, automatically reroutes the unrecognized mail item from the main conveying path to a resorting position, which is either likewise connected to the translator, and in which the code letters are only 25 picked out in accordance with another rule, or in which the sorting is effected manually.

Among others, the invention bears the advantage that the translator can be designed to have a relatively small size. Furthermore, the keying time is reduced to a 30 minimum. In addition thereto the unrecognized mail items are prevented from being fed or routed to the letter-facing or stamp-cancellation device respectively, so that the latter can already start to handle the next successive mail item, in cases where the translator is immediately switched to receive information from the next 35 operator's position.

The above mentioned and other features and objects of this invention and the manner of attaining them will become more apparent and the invention itself will be 40 best understood by reference to the following description of an embodiment of the invention taken in conjunction with the accompanying schematic drawings, in which:

FIG. 1 shows the novel type of article sorting control arrangement,

45 FIG. 1a shows the series-parallel converter 8,

FIG. 1b shows the translator arranged between the outputs of the series-parallel converter 8 and the coincidence circuits 9.

As shown in the drawing, the conveying path of a mail 50 sorting machine is designated by the heavy black lines and which conveying path extends from operators positions 1 to deflector device 2 to a mail processing device 4. The device 4 constitutes no part of the invention and, therefore, it is shown as a rectangle. It may either be 55 a stamp cancelling device or a letter facing machine, both of which are well known in the art. The deflector devices 2 are arranged to feed into an alternate conveying path which leads to the resorting operator's position 3 and thence to the processing device 4. The mail deflecting devices 2 are of a known type and the left-deflecting device shown in the drawing, is in its switched position so 60 that mail coming from the left-most operator's position 1 will be deflected to the alternate path leading to the resorting operator's position 3. Both deflecting devices 2 to the right of the drawing are shown with their switch 65 positions set to lead directly into the processing apparatus 4.

Each operator's position 1 consists of a keyboard device 5 and an indicating device 5a. The indicating device 70 may be of any suitable type and is not further described. The keyboards 5 are of known types, for example as shown in U.S. Patent 2,741,662 issued April 10, 1956

and are adapted to be keyed by an operator in accordance with a particular code, for example, each key of the keyboard may represent a letter and may correspond to a printing telegraph keyboard which is adapted to transmit a five-unit code (or a lesser code, as is known to the art) to a connecting device 6. The connecting device 6 is similar to a telephone line finder which may sequentially scan the output leads from respective of the operators positions 1. Such a device is well known to those skilled in the art. One example of such a scanning mechanism or line finder is shown in FIGURE 42, page 395 and is described on page 391 and on page 399 of the book "Handbook for Telephone Managers and Engineers," B. C. Burden, Editor, published by the Automatic Electric Company, Northlake, Illinois, 1957 edition. Another example of a line finder is given in the book "Telephony," vol. II by J. Atkinson, 1950, Pittman and Sons, London. On page 620, FIGURE 605 and discussion on page 621 and in FIGURE 603, page 619, various line finder arrangements are described. There are other types of known apparatus suitable for the scanner 6 also. All that is necessary is that the scanner 6 sequentially connect the output of one of the keyboards, such as 5, through the scanner 6 to the translating device 7. When one keyboard operator at 1 has sent in a particular address, the scanner 6 will then connect the next keyboard 5 to the translator and so on, so that the keyboards 5 at the various operator positions 1 are sequentially connected to the translator 7 for short periods of time.

The connecting device 6 is connected to a translation device 7 by a suitable line. The device 7 comprises converter 8 consisting of shift registers "a" through "e" capable of storing a suitable number of code combinations. The shifting registers may be of any known type, such as a neon tube register, a magnetic core register, etc., it being necessary only to store the several code combinations which may be keyed into it from any operator's position and representing given sequences of a mail destination, for instance, the first, third, fourth and last letters of a destination name. A typical form of a shift register using magnetic cores is shown in FIGURE 5-14 and described on pages 221 through 223 of the book "Digital Computer Components and Circuits" by R. K. Richards, 1957, Van Nostrand Company, Princeton. Additional types of shift registers are shown in the same book in FIGURE 5-2, page 192 and FIGURE 5-11-c, page 214. The design and construction of such shift registers are well known in the art and any of several types available may be picked for convenience for use as the shift registers a, b, c, d, e in FIGURE 1a. It should be understood that the particular letters chosen are arbitrary and any other suitable selection might be arranged if desired. The shifting registers "a" through "e" serve as a translator, which may conveniently be a series parallel converter.

According to the showing of FIG. 1a there are provided five shift registers a . . . e, corresponding to the five positions of the teleprinter code by which the letters of the destination names are represented. The individual letters are respectively stored in parallel on the five lines f . . . j into the respective shift registers. For each destination name there are used four letters, which are successively keyed-in. Therefore, for each shift register there are provided four storage cells. The storing-in on the five lines f . . . j is respectively effected synchronously into the first column. At the next letter the contents is shifted further by one column, so that finally all four letters are stored fully in parallel. The parts of the circuit arrangement which are necessary for operating the shift registers are not shown in the drawings, because they are considered to be well-known to the one skilled in the art.

The converter 8 has a plurality of parallel outputs 11 . . . 30, there being one output for every possible recognizable sequence of identification or code letters. Each pair of parallel outputs correspond to a different

destination and are coupled to different ones of coincidence circuits 9. These circuits are well known and require the coincidence of two inputs to render them operable and are better known as "AND" gates.

FIG. 1b shows one such translator circuit serving the first four letters of the destination name "Washington." Of the outputs 11 . . . 30 the outputs 11 . . . 15 are respectively assigned to the first, the outputs 16 . . . 20 to the second, the outputs 21 . . . 25 to the third, and the outputs 26 . . . 30 to the fourth letter. This is illustrated in FIG. 1b by the four bordered or encased groups of five outputs each.

If it is assumed now that the letter "W" includes the first and the fourth position, the letter "H" includes the first, second and fourth position, the letter "S" includes the third and fourth position, the letter "N" includes the second, third, fourth and fifth position of the five-unit code.

The aforementioned positions then are the marked outputs (solid or fat lines) and are all connected with the gate 9a; the other positions then are the non-marked outputs (thin lines) and correspondingly connected with the gate 9b. The outputs of these two gates are led to the "AND" gate 9, at the output of which the name of "Washington" will be indicated as being recognized upon appearance of an output signal.

The outputs of the different coincidence circuits 9 represent a different destination as shown, and are coupled to the mail processing apparatus 4. Thus, if the destination of a mail item is keyed into the keyboard 5 by an operator, and the code he has keyed corresponds to the city of Berlin, for instance, the converter 8 recognizes such a destination. Since the apparatus is adapted to recognize same, the mail item will proceed on the conveying path from the operator's position to the mail processing device and the outputs from the relevant coincidence circuit will cause the processing device 4 to operate. Of course, the relevant deflecting device 2 will be set for a through passage of the mail item from the relevant operator's position 1 to the device 4.

Let us now assume that the operator erroneously keys into his keyboard an erroneous destination not recognizable by the device 7, then at none of the outputs of the coincidence circuits 9 there will be produced an output signal. Furthermore, the outputs, of the "AND" gates 9 are connected with a "NOT" gate 9c for effecting that then and only then when no signal appears in the operating rhythm at one of its inputs, an output signal will appear at the "NOT" gate 9c. The output of "NOT" gate 9c is connected with the one input of the "AND" gates 10. The output of the "NOT" circuit 9c connected in parallel to a plurality of additional coincidence gates 10 and which gates are likewise "AND" gates. The gates 10 are adapted to open upon the simultaneous application of a signal from a corresponding operator's position 1 and a signal from a "NOT" gate circuit 9c. The operation of a gate 10 will cause the associated deflecting device 2 to switch the conveying to the operator's position 3. This will occur when the operator has keyed in a destination not catered for by the device 7. Whenever this situation occurs a warning device 5a will be actuated to notify the operator that either an erroneous designation has been keyed or a designation not catered for by the apparatus has been keyed. The conduction of the "NOT" gate 9c would also cause the connecting device 6 to be switched to a succeeding operator's position so that the device 7 may immediately evaluate information relating to another piece of mail, and thus maintain the system in constant operation. Thus items of mail which are deflected by the devices 2 are sent to the resorting position 3 and which position is connected to the device 7 by means of the electrical path 3a. It is intended that if the destination and the rejected piece of mail is capable of being handled by the evaluation device 7, that it will be sent on to the processing apparatus 4 from the position 3.

If, however, the destination is one that should not be catered for by the translating device 7, the operator may manually sort or extract the offending mail item.

The invention is adapted to permit the use of a relatively simple recognition code, such as keying the first, third, fourth and last letters of a destination. For instance, if the name "Washington" appeared on a mail item, an operator would depress the keys "W," "S," "H" and "N," respectively, in that order. Assume that with such a code, two destinations are possible having the same 1, 3, 4 and last letters. The evaluation device can be preset to reject both of these destinations and the "NOT" gates 9c could be made to operate as previously explained. In practice there will be few destinations which have identical first, third, fourth and last letters, and mail items to such destinations may be manually handled in the resorting operator's position 3. The bulk of the mail items handled will have destinations which are unique as far as the evaluation device 7 is concerned and, therefore, the simplest possible coding arrangement may be utilized, as explained hereinabove.

While we have described above the principles of our invention in connection with specific apparatus, it is to be clearly understood that this description is made only by way of example and not as a limitation to the scope of our invention, as set forth in the objects thereof and in the accompanying claims.

What is claimed is:

1. An article sorting arrangement comprising a plurality of operators' positions for keying a code corresponding to the destination of said articles to be sorted, a processing means, a conveying path extending between each of said

25

30

operators' positions and said processing means, an article deflecting means in each of said conveying paths adapted when operated to deflect said article from said conveying path, translating means common to said operators' positions for decoding said destination code connecting means for sequentially connecting said operators' positions to said translating means on a one-at-a-time basis, said translating means including circuit means for providing a control signal indicative of the destination of said article, gate means operable responsive to the non-appearance of said control signal for operating said deflecting means and said connection means to deflect said article from said conveying path and to advance the said connecting means to a different operator's position.

5 15 2. An article sorting arrangement as claimed in claim 1, wherein said translating means further includes shift registers in parallel to store the code corresponding to the destination of the article to be sorted.

10 20 3. An article sorting arrangement as claimed in claim 1, further comprising an additional conveying path coupled to each of said article deflecting means, said additional path adapted to receive articles deflected from their associated conveying paths upon operation of the associated article deflecting means.
